UNITED STATES PATENT OFFICE.

ALLEN CLAAPP FARRAR, OF WHITMAN, MASSACHUSETTS.

PROTECTED LAST.

Application filed March 27, 1924. Serial No. 702,293.

My present invention is a novel and improved method of protecting the heel portions of lasts, used in boot and shoe manufacture, and includes also a novel form of 5 protecting member for the last cone.

Boot and shoe lasts as employed in modern shoe factory methods, are subjected to very great pressures, strains and compression, particularly during the heeling, leveling, sole laying and such like operations. 10 The last is made of wood and the compressive strains incident to heel nailing, leveling, etc., exerted thereon, quickly breaks down the wood of the last, particularly when 15 the last is not seated squarely upon the last jack and between the jack and the moving part of the machine in which the last may be for the particular operation, sole laying, leveling, heel nailing and the like. A further frequent cause of the breaking of the 20 lasts, is the fact of the uneven thicknesses of sole, insole, upper materials, as well as heels, thus imparting a greater tension on one side of the last than on the other, resulting in the 25 breaking of the wood of the last on that side upon which the greater strain first comes. As leather and upper materials are constantly varying in thicknesses, and as the heel nailing machines for example are usually 30 set for a predetermined thickness, the difficulty above pointed out, is constantly present, and constantly varying.

In my present invention, I have provided means which both protect the cone of the 35 last and also provides for an automatically self-seating, or adjustment of the last and its assembled shoe thereon, between the last jack on which the last rests, and the plunger or other moving portion of the machine 40 exerting the compression. My method is, briefly, to so protect the heel part adjacent the last jack, that the last may have a sufficient rocking or adjustable movement when the plunger or moving part of the machine 45 in which the last is applied for the heel nailing, laying, etc., operations, that it will automatically compensate for any unevennesses in thickness, or strains, tensions or the like, and insure the presentation of the 50 entire heel portion of the last fairly and squarely under the plunger and thus transmit the compressive strains incident to such operations, squarely upon the last jack without undue or breaking strains on either 55 side, front or rear. Thus my method consists in applying a movable or rocking last

protector on the cone of the last, and thereby permitting the last itself to be rocked upon the jack, effecting a self-adjustment or self-seating as the strain of the machine 60 increases or is applied to the heel, sole or last bottom. I believe that this is a distinct novelty in the method of last protection, and also a novel form in the protecting device on the last itself, and I wish to claim 65 both these features herein broadly.

Referring to the drawings, illustrating a preferred embodiment of my invention:—

Fig. 1 is a view of a typical hinge last in position to be applied to a jack or last support; 70

Fig. 2 is a cross-sectional view on the line 2—2 of Fig. 1; and

Fig. 3 is a small diagrammatic view illustrating the last on a jack or last support. 75

It will be appreciated that my invention is applicable to any type of last, whether block last, hinge last, slide last, link last or the like, the important feature consisting in the heel protection and the carrying out of 80 my present method. As herein shown a typical hinge last is illustrated with the forepart 1 and heel part 2, the latter fitted with the usual tube or thimble 3. A clenching plate 4 on the last bottom is also shown and on the cone or top of the last is provided my novel form of protecting plate 5. This plate may be of metal, hard fiber or other suitable compound, or may comprise a plurality of layers, with a metal or fiber exterior 85 and an intermediate cushioning layer, as indicated in dotted lines at 6, Fig. 1. In either case, the main protecting member 5 of metal or hard fiber, is formed of rocker shape, i. e., with a curved surface 10. This curved surface preferably curves both laterally and longitudinally from the juncture of the thimble 3 with the protector 5, the protector 5 being bored for this purpose to receive the thimble and preferably also being 90 recessed slightly as shown at 12 to receive the flange 14 of the thimble 3 and thus the thimble and flange may be flush with the surface 10. This is not essential as the small extent of the flange 14 will not prevent the entire shoe rocking upon the last support 15 and last jack 16, which latter fits within the thimble 3. Thus when the plunger 20 or moving part of the machine in which the last and shoe are applied, strikes the bottom surface or heel plate 4 of the last, the last itself may automatically be 100 105 110

straightened by rocking on the surface 10 to insure an even distribution of strains and compression throughout the entire extent of the wooden portion 2 between the plate 5 and plunger 20. Thus the last parts and particularly the side portions of the cone of the last at 21, which are comparatively narrow and the thinnest part of the wood, will not be broken down by undue compressive strains.

I believe that my method of last protection will insure long life and usefulness in wooden lasts and take the place of many expensive efforts to protect lasts heretofore attempted.

My invention is further described and defined in the form of claims as follows:—

1. A last, having a protecting plate upon the heel portion thereof adjacent the thimble

opening, the thimble extending through and 20 securing said plate to the last, said plate having a convex form to permit the rocking of the last on the support during heel nailing, sole laying, and the like operations.

2. A last, having a protecting plate upon 25 the heel portion adjacent the thimble opening, an opening in the plate aligned with the thimble opening, a circumferential recess around the outer edge of said plate opening, the thimble extending through said 30 plate and being flanged in said recess to secure said plate to the last, said plate having a convex form to permit the rocking of the last on the support during heel nailing, sole laying, and the like operations.

In testimony whereof, I have signed my name to this specification.

ALLEN CLAPP FARRAR. 35
